US00D751418S

(12) United States Design Patent
Fan

(10) Patent No.: US D751,418 S
(45) Date of Patent: * Mar. 15, 2016

(54) PACKAGING BOX WITH BALL

(71) Applicant: NIKE, Inc., Beaverton, OR (US)
(72) Inventor: Richard S. Fan, Portland, OR (US)
(73) Assignee: NIKE, Inc., Beaverton, OR (US)
() Term: 14 Years
(21) Appl. No.: 29/520,775
(22) Filed: Mar. 17, 2015
(51) LOC (10) Cl. 09-03
(52) U.S. Cl.

CLAIM

The ornamental design for a packaging box with ball, as shown and described.

DESCRIPTION

FIG. 1 is a front perspective view of a packaging box with ball showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

The broken lines shown represent unclaimed subject matter and form no part of the claimed design.
